SELF-CLEANING SPARK PLUG CLEANER

George Persak, Jr., Verona, N. J., assignor to The Oiljak Manufacturing Co., Inc., Montclair, N. J., a corporation of New Jersey

Application August 12, 1957, Serial No. 677,653

6 Claims. (Cl. 51—8)

The invention here disclosed relates to spark plug cleaners of the type shown in Patents 2,505,422 April 25, 1950, 2,552,344 May 8, 1951 and co-pending patent application Serial No. 587,809 filed May 28, 1956, wherein cleaning is effected by the scouring action of a sharp abrasive such as garnet.

An important object of the present invention is to accomplish an automatic cleaning of the abrasive as it is used, so as to keep it in effective scouring condition.

This object has been attained by a double screening operation, wherein the air carrying the material scoured from the plugs is released through a first screen and caused to drop the abrasive into a central abrasive hopper and is then released to atmosphere through a second filter wall surrounding and spaced from the first screen and thereby caused to drop the removed waste, generally in finely powdered form, into a separate dust collecting hopper below and spaced from the abrasive hopper.

Special objects of the invention are to provide an efficient screening and filtering structure, which can be produced at low cost and made up in a simple substantial structure, readily assembled and taken apart and which in particular, will enable quick easy removal of the dust separated from the abrasive and, when so desired, the quick easy removal of the abrasive.

Other desirable objects and the novel features of construction through which the purposes of the invention are attained are set forth and will appear more fully in the following specification.

The drawings accompanying and forming part of the specification illustrate a present commercial embodiment of the invention, but structure may be modified and changed as regards the immediate illustration, all within the true intent of the invention as hereinafter defined and claimed.

Fig. 1 in the drawings is a broken vertical sectional view of one of the new self-cleaning spark plug cleaners.

Fig. 2 is a broken sectional view showing how the inner, abrasive hopper is separated from the upper head of the abrasive holder by spacing struts.

Figs. 3 and 4 are broken sectional views of the abrasive nozzle and the air blast cleaning nozzle structures respectively.

Figs. 5 and 6 are cross-sectional views on substantially the planes of line 5—5 and 6—6 of Fig. 1.

Fig. 7 is an elevation of the filter-cleaner bag as made up for installation.

Fig. 8 is a part sectional view of the same showing it reversed ready for mounting in the apparatus.

The embodiment of the invention illustrated, comprises an inverted can top 7, having dependent spacer struts 8, supporting an abrasive hopper 9, a larger diameter dust hopper 10, spaced below the abrasive hopper, a first abrasive catching screen 11, stretched between the can top and abrasive hopper and a dust catching filter wall 12, stretched between the can and the rim of the larger diameter dust hopper 10.

A pickup tube 13, dipping down into the abrasive hop-

2

per supplies fresh abrasive to the nozzle 14 under lift of air furnished by connections 15, and similar connections 16, supply cleaning air to an air-blast nozzle 17.

A rubber adapter 18, seated in the top of the can provides support for the plugs being cleaned.

The abrasive nozzle and pickup tube are shown carried by a U-bracket 19, dependent from the can top.

The abrasive filter 11 and dust arresting screen 12, are indicated as inner and outer walls of a single bag structure having a doubled edge 20, at the top held to the dependent flange portion 21, of the can by a surrounding clamp band 22, and with the inner wall 11, secured about the flange 23, of the abrasive hopper by clamp band 24, and the outer wall 12, held to the flange 25, of the dust hopper by clamp band 26.

While these filter and screen walls may be of the same or similar material and possibly actually parts of the same bag reversed on itself, it has been found best to make the cleaner bag as indicated in Fig. 1a with an inner cylindrical filter wall 11, of polyethylene fabric and an outer 20 downwardly flaring dust arresting wall 12, of canton flannel disposed with the nap inside.

The cylindrical filter 11, is shown stitched at 27, to the inturned edge of the upper end of the canton flannel dust arrestor and as having a canton flannel tape 28, stitched about the lower edge of the same, thus providing resilient flannel gripping and sealing means for the three clamp bands 22, 24 and 26. The latter are shown in Figs. 5 and 6 as having screw fastenings 29, 30, 31, enabling ready mounting and unmounting of the screening fabrics.

The outer, larger dust collecting hopper 10, is shown as spaced a definite distance below and away from the inner hopper 9, by spacing lugs 32, on the inside in abutment with the inner hopper and as positively secured in this relation by a wing nut 33, on a screw stud 34, dependent from the inner hopper.

This fastening also serves to hold in place a cap or cover 35, closing a dust discharge opening 36, in the bottom of the hopper. A resilient washer 37, is provided to keep the cover dust tight.

On removal of the dust drain cover 35, access may be had to the abrasive hopper for the purpose of draining out the abrasive.

A second wing nut 38, on screw stud 34 is shown holding a cap 39, and washer 40, in place over drain openings 41, in the bottom of abrasive hopper 9. On release of this second wing nut, this inner cover may be opened to discharge abrasive from the inner hopper.

In operation of the invention with either the abrasive nozzle 14, or the air blast nozzle 17, fine dust scoured from the spark plugs will be carried by the air through the inner filter wall 11, out into the surrounding truncated chamber 42, defined by the outer dust arresting wall 12, and with resulting drop in pressure, be deposited in the lower dust hopper 10. Agitation occurring in the operation of the machine assists this abrasive cleaning and dust separating action. The waste or dust accumulated in the outer, lower hopper may be removed at any time on removal of the cover in the bottom of this hopper and similarly, abrasive may be removed from the inner hopper on releasing or taking off the cover closing the bottom of that hopper. The constant removal of the waste keeps the abrasive clean and sharp, so that abrasive may be used practically continuously without need for changing but possibly requiring some addition to replace worn or more finely pulverized material.

The lantern made up of the inverted can top 7 and hopper 9 spaced below the same forms a frame for the abrasive screen 11 and a base supporting all essential parts including the spark plug holder, abrasive and air blast nozzles, the outer dust arresting screen 12 and the

lower, dust collecting hopper 10. The parts are thus combined in a simple compact unit and this is adapted for mounting as such in any suitable supporting stand, cabinet or the like. In the illustration, the top is shown as having outstanding brackets 43 for mounting it in a cabinet, table or other supporting structure 44.

The flexible fabric screens are more or less free to vibrate and thus to automatically clear themselves, the inner one of abrasive and the outer one of dust. The flaring, outward and downward inclination of the outer screen assists in this self-clearing action.

By making the doubled screen as an open ended bag with the lower end portion of abrasive screening material and the upper end portion flared out to larger diameter and of dust arresting material, the entire screening medium may be handled as a single unit, doubled on itself midlength, secured at the top to the can and at the bottom to the inner and outer abrasive and dust hoppers.

The screw 33 securing the dust release cap 35, serves through the medium of this cap, to positively secure the dust hopper in spaced relation to the abrasive hopper. On release of this screw, however, the dust hopper will still be supported at such time by means of the dust arresting screen 12.

What is claimed is:

1. Self-cleaning spark plug cleaner, comprising the combination of abrasive spark plug cleaning nozzle, abrasive containing chamber about the same having an upright annular abrasive retaining filter wall, a dust collecting chamber surrounding and spaced from said abrasive chamber having an upright annular dust arresting wall, said abrasive chamber having an abrasive confining hopper at the bottom of said upright filter wall, said dust collecting chamber having a dust confining hopper at the bottom of said upright dust arresting wall of larger diameter and spaced from said abrasive hopper, said dust hopper having a removable closure at the bottom of the same for removal of dust accumulated in said dust collecting chamber and said abrasive hopper having a releasably confined closure for enabling removal of abrasive.

2. Self-cleaning spark plug cleaner comprising a support for a spark plug to be cleaned, a nozzle positioned to direct a blast of scouring medium at a spark plug so positioned, an abrasive confining enclosure about said nozzle and spark plug being cleaned including a porous wall of abrasive screening fabric and an abrasive holding hopper at the foot of said wall, a dust arresting chamber in spaced relation about said abrasive confining enclosure and including a porous wall of dust arresting fabric in spaced relation about said abrasive screening wall and a dust collecting hopper at the foot of said dust arresting wall, of larger diameter than and spaced below said abrasive holding hopper.

3. The invention according to claim 2, in which said dust collecting hopper has a dust discharge opening at

the center of the same provided with a removable closure and said abrasive holding hopper has a central abrasive discharge opening provided with a removable closure above and accessible when said dust removal closure is removed.

4. Self-cleaning spark plug cleaner comprising a support for a spark plug to be cleaned, a nozzle positioned to direct a blast of scouring medium at a spark plug so positioned, an abrasive confining enclosure about said nozzle and spark plug being cleaned including a porous wall of abrasive screening fabric and an abrasive holding hopper at the foot of said wall, a dust arresting chamber in spaced relation about said abrasive confining enclosure and including a porous wall of dust arresting fabric in spaced relation about said abrasive screening wall and a dust collecting hopper at the foot of said dust arresting wall, of larger diameter than and spaced below said abrasive holding hopper, said abrasive screening wall and dust arresting wall being secured together at the top and the inner abrasive screening wall secured at the bottom to the abrasive hopper and the outer dust arresting wall being secured at the bottom to said dust collecting hopper.

5. Self-cleaning spark plug cleaner comprising a support for positioning a spark plug to be cleaned, a nozzle located to direct a blast of abrasive medium at a spark plug so positioned, an abrasive confining enclosure about said nozzle and the spark plug being cleaned, including an upright cylindrical plastic wall of abrasive screening material and a dust arresting chamber about said cylindrical abrasive screening wall and including a wall of porous napped fabric spaced outwardly away from said abrasive screening wall.

6. Self-cleaning spark plug cleaner comprising a support for positioning a spark plug to be cleaned, a nozzle located to direct a blast of abrasive medium at a spark plug so positioned, an abrasive confining enclosure about said nozzle and the spark plug being cleaned, including an upright cylindrical wall of abrasive screening material and an abrasive holding hopper at the lower end of said abrasive screening wall, a dust arresting chamber about said cylindrical abrasive screening wall including a dust arresting porous fabric wall surrounding said cylindrical abrasive screening wall and extending from the upper end of said abrasive screening wall on a downward and outward incline providing annular dust containing space about said cylindrical abrasive screening wall and a hopper connected with the lower larger end of said dust arresting wall below and spaced away from said abrasive holding hopper.
